UNITED STATES PATENT OFFICE.

FRANK LAWTON, OF LEOMINSTER, MASSACHUSETTS.

DESIGN FOR A FRAME FOR MUSIC-LEAF TURNERS.

SPECIFICATION forming part of Design No. 35,317, dated November 26, 1901.

Application filed October 10, 1901. Serial No. 78,278. Term of patent 14 years.

To all whom it may concern:

Be it known that I, FRANK LAWTON, a citizen of the United States, residing at Leominster, in the county of Worcester and State of Massachusetts, have invented and produced a new and original Design for a Frame for a Music-Leaf Turner, of which the following is a specification, reference being had to the accompanying drawings, forming part thereof.

Figure 1 of the drawings is a view in perspective of a frame for a music-leaf turner, showing my new design. Fig. 2 is a view in front elevation of the same.

The leading or material feature of my new design consists of the frame of generally rectangular form, having the two upper corners truncated, as shown at 1 1, the side bars 2 2

terminating at their upper end below the plane of the middle portion 3 of the top bar having depressed ends 4 4, and the lower ends 20 of the side bars depending below the plane of the bottom bar 5, as shown at 6 6. The side bars are shown cylindrical and the top and bottom bars flat.

What I claim as new, and desire to secure 25 by Letters Patent, is—

The design for a frame for a music-leaf turner, as herein shown and described.

In testimony whereof I have hereunto set my hand this 13th day of September, 1901.

FRANK LAWTON.
